UNITED STATES PATENT OFFICE.

WILLIAM J. REHRIG AND WILLIAM O. HOPPE, OF LOS ANGELES, CALIFORNIA, AS
SIGNORS TO SAID WILLIAM J. REHRIG.

BOTTLE CASE.

Application filed May 20, 1927. Serial No. 192,902.

Our invention relates to improvements in bottle cases, the primary object being to provide a case or crate having greater strength and which is more durable than heretofore and which is less complicated and expensive in construction. It is of prime importance that a case which is employed for carrying milk bottles and other receptacles shall be thoroughly sanitary, easily cleaned and light in weight. These objects are attained by our invention.

To these ends our invention comprises the features of construction and combination of parts hereinafter described and claimed.

In the accompanying drawing forming part of this specification, Fig. 1 is a plan of our improved case; Fig. 2 is a section taken on the line 2—2 of Fig. 1; Fig. 3 is an enlarged section of a detail taken on line 3—3 of Fig. 2; Fig. 4 is another section of a detail taken on the line 4—4 of Fig. 2, and Figs. 5 and 6 are perspective views of details illustrating the method employed in the construction of the partitions.

In the drawing, A, B, C, and D indicate the four sides of our improved case, the lower edges of which are reinforced and protected by the channel members 10. This structure is reinforced by two longitudinal and three transverse vertical groups of partition members which divide the case into individual bottle holding compartments. The two longitudinal groups are each composed of three rods 11, 12 and 13, suitably spaced vertically apart to form skeleton walls for holding the bottles or other receptacles and the three transverse groups are each composed of three rods 14, 15 and 16 also suitably spaced vertically apart to form skeleton walls. The bottom or floor of the case is formed by a pair of horizontally disposed rods 17 and 18 extending longitudinally below each compartment. The ends of all of said partition and floor rods are secured through the walls of the case by riveting their ends, thus reinforcing the strength and rigidity of the structure. This strength and rigidity is augmented by a vertical rib member E, extending transversely across the central lower portion of the body of the case and spaced above the channel member 10, to provide clearance when two or more cases are stacked. Said rib member is split and formed into elongated loops 19, distributed from end to end and near the upper edge thereof, through which

the lower rod 16 of the central group of transverse rods (14, 15 and 16) is threaded to freely suspend the rib member. The rib member is corrugated at 20 to increase its rigidity and the longitudinal rods 13 of the partition members and 17 and 18 of the floor members pass freely through its lower portion. Vertically disposed supporting members F and G, which resemble straps, have their upper ends looped around the upper rod 14 of the central group of transverse partition rods and the lower ends of said straps engage the rib member E below the transverse rod member 16 and are engaged thereto by the lower longitudinal rod members 13. The longitudinal rods 11 and 12 perforate and engage the supporting members F and G. Said supporting members are split and formed into loops 21 to freely receive and engage the member 15, of the central group of transverse rod partition members. In this manner all of the members of the structure are freely tied together to permit limited movement of the parts without substantially decreasing the strength of the entire structure. The method of fastening the partition, floor, rib and strap members together, serves to produce a structure which is strong and durable. The ends of the rib member abutting against the sides D and B also assist in bracing the parts together. The perforations in the rib member E, through which the rods 13, 17 and 18 pass are sufficiently larger in diameter to provide a loose fit and permit free movement of the rib member on said rods and free deflection of the lower portion thereof when striking an object. The rib member being hinged or swung from the rod 16 by the loop 19 also permits deflection of the rib member E without becoming permanently bent in the event of striking an object below as often occurs during stacking and the severe rough handling to which cases of this character are frequently subjected.

In accordance with the patent statutes, we have described the principles of operation of our invention, together with the apparatus which we now consider to represent the best embodiment thereof but we desire to have it understood that the construction shown is only illustrative and the invention can be carried out by other means and applied to uses other than those above set forth within the scope of the following claims.

Having described our invention what we

claim as new and desire to protect by Letters Patent is:

1. A case having four side walls, intersecting skeleton partitions formed by intersecting rods across the space between said walls dividing said case into compartments, rods forming a skeleton floor across the lower portion of each of said compartments, a substantially vertical rib member across said case with which said floor members are freely and movably engaged, and a support journaled lengthwise to the upper portion of said rib member and secured to the opposite sides of said case and adapted to permit the lower portion of said rib member deflecting.
2. A case having four walls, skeleton partitions formed by intersecting members across the space between said walls and dividing said case into receptacle receiving and holding compartments, a skeleton floor across the lower portion of each compartment, a substantially vertical rib member hung freely from its upper portion across said case by which said floor members are engaged through free openings to permit the rib member deflecting, and an upwardly extending support secured to the median portion of said rib and intersecting partition members, for the purposes specified.
3. A case having four side walls, intersecting skeleton partitions formed by intersecting rods across the space between said walls dividing said case into compartments, a

skeleton floor across the lower portion of each compartment, and a rib member across the median portion of said case with which said floor and partition members are engaged, said rib member being disposed substantially vertically and on edge and being provided with openings through which the floor members pass freely to allow free deflection of the lower portion of the rib member.

4. A case having four side walls, skeleton partitions formed by intersecting members across the space between said walls dividing said case into receptacle receiving compartments, skeleton floor members across the lower portion of said compartments, a corrugated substantially vertical rib member across the median portion of said case by which said floor members are movably engaged to permit free deflection of the lower portion of the rib member, a transverse rod threaded longitudinally through the upper portion of said rib member and tied to the opposite side walls of said case to permit the rib member swinging freely and a pair of supports secured to said rib member extending upwardly and attached to the median portion of said partition members, for the purposes specified.

In witness whereof we have signed our names to this specification.

WILLIAM J. REHRIG.
WILLIAM O. HOPPE.
